UNITED STATES PATENT OFFICE.

ROBERT EDWARD TURNER, OF BOSTON, MASSACHUSETTS.

BUNION SHIELD OR PROTECTOR.

1,073,185.

Specification of Letters Patent. Patented Sept. 16, 1913.

Application filed March 29, 1912. Serial No. 687,086.

To all whom it may concern:

Be it known that I, ROBERT EDWARD TURNER, a citizen of the United States, and a resident of Boston, county of Suffolk, and 5 State of Massachusetts, have invented an Improvement in Bunion Shields or Protectors, of which the following description, in connection with the accompanying drawings, is a specification, like characters on the 10 drawings representing like parts.

This invention relates to bunion shields or protectors and more particularly to those of that type in which the shield or protector is provided with an opening or recess 15 to receive the bunion and relieve it from the pressure of the boot or shoe or other foot covering.

The invention has for its object and aim among other things to provide a bunion 20 shield of the general character above referred to which shall be efficient in operation, easily applied and removed, and readily and quickly adjustable to feet of any size or shape whatever may be the location 25 of the bunion. These and other features of the invention will best be understood from the following description, taken in connection with the accompanying drawings of a 30 bunion shield embodying one form of the invention for illustrative purposes, the scope of the invention being more particularly pointed out in the appended claims.

Referring to the drawings: Figure 1 shows a bunion shield, embodying one form 35 of the present invention, in place upon a right foot; Fig. 2 is a top plan view of the bunion shield shown in Fig. 1 with the attaching means relaxed preparatory to applying the shield to the foot; Fig. 3 is a top 40 plan view of the bunion shield in Fig. 1, with the attaching means drawn taut and secured in position as it would be after the shield has been applied to the foot; Fig. 4 is a side elevation of the shield shown in 45 Fig. 1; Fig. 5 is a longitudinal, vertical section on the line 5—5 of Fig. 1.

In the illustrative embodiment of the invention shown in the drawings, the pad or shield proper consists of a substantially 50 egg-shaped piece of felt 2, although it will be understood that it may be composed of any other suitable material or may be of any other suitable shape without departing from the spirit of the invention. White 55 felt has been found well adapted for this

purpose. The shield 2 is preferably beveled or skived off around its outer edge at 4, upon that side which forms the outer surface thereof, when it is positioned upon the foot as shown in Fig. 4. The opening 6 for 60 the reception of the bunion will preferably be located nearer the narrower end portion of the egg-shaped shield and preferably also nearer the edge which forms the lower edge of the shield when the latter is in position upon the foot, and the material will 65 preferably be beveled around the edge of the opening 6 upon that surface of the shield which is in contact with the foot. By referring to Fig. 1, it will be seen that 70 by locating the opening as described, the greater part of the shield is back of the bunion when the latter is in position, which is a great advantage.

Suitable means are provided for securing 75 or attaching the shield to the foot, said means in the embodiment of the invention shown comprising a band or tape 8 having one end secured, as at 10, to the outer surface of the shield by stitches 12, or in any 80 other suitable manner. The other or free end portion 14 of the tape passes under a suitable guide herein consisting of a relatively short piece of tape 16 suitably secured adjacent its two ends to the shield 85 upon the latter's outer surface, as by stitches 18, or in any other suitable manner; the tape 8 thus passing relatively loosely between the said guide 16 and forming the loop 20. Suitable means are herein provided for adjustably securing the free end 90 portion 14 to the pad, said means herein consisting of a piece of thread 22. Preferably the piece of thread will first be threaded through the tape 8, as at 24, adjacent the 95 latter's free end which will preferably be turned over, as shown at 26 in Fig. 4, to give added strength to the end portion of the tape; and then through the material of the shield in substantially the longitudinal 100 direction of that portion of the tape that passes under the guide, the thread emerging from the shield and passing upwardly through the tape at 32. The thread then passes downwardly through the tape at 34 105 and into the material of the shield, from which it emerges at a point intermediate the point 32 and the free end of the tape, and passes upwardly through the tape at 40, and then downwardly through the tape at 110

42, and into the material of the shield again, from which it finally emerges adjacent the free end of the tape and passes upwardly through the latter as at 48. While the described manner of threading has been found well suited to permit the shield to be readily adjusted, it will be understood that any other manner of threading that will permit the thread to run freely may be used without departing from the spirit of the invention.

To apply the shield to the foot, assuming that the bunion is on the metatarsal joint of the great toe, the loop 20 is passed over the great toe and the pad, then adjusted upon the foot so that the bunion is properly located in the opening 6. If the loop 20 is not sufficiently large to enable this to be done, it is only necessary to draw upon the tape in the direction of the arrow in Fig. 2 whereupon the thread 22 will run freely through the holes and thus allow the required length of tape to be readily drawn forwardly through the guide 16. The shield having been positioned upon the foot, as described, with the loop 20 extending around the great toe and the bunion being properly located in the opening 6, the person applying the shield will hold the latter in this position, and then, seizing the free ends 50 and 52 of the thread 22, will draw steadily upon the latter. The tape will thus be drawn backwardly through the guide 16 until the loop is drawn snugly down between the great toe and the next one and snugly embraces the great toe, and the thread will be drawn taut thus securing the tape in its newly adjusted position. The free ends 50 and 52 of the thread are now knotted at the points where they emerge through the free end of the tape so as to secure the free end of the tape in close contact with the outer surface of the shield, as shown in Fig. 3.

So far as I am aware, all bunion shields heretofore used have been applied to the foot with the aid of cement, the latter being used either upon that surface of the shield that is in contact with the foot or else upon bands or tapes that are laid across the shield or along its edges after it has been positioned upon the foot, the portions of said tapes extending beyond the shield being cemented to the foot. It is believed that attempts have been made heretofore to provide a bunion shield that could be applied to the foot and held in place by means of a rubber band, but so far as I am aware these attempts were not a success as it was found that in order to securely hold the shield in place the tension of the band had to be so great as to seriously interfere with the circulation; this, and the consequent great pressure exerted by the shield upon the flesh in the vicinity of the bunion, aggravated the trouble instead of relieving it. As a result,

so far as I am aware, either cement or some other adhesive is used in attaching all bunion shields heretofore used to the foot.

It will be apparent that the bunion shield constructed in accordance with the present invention offers many advantages over those above referred to. When a bunion shield is applied to the foot with the aid of an adhesive in whatever form the latter may be used, the shield is necessarily stiffened by the presence of the adhesive and cannot be removed without considerable trouble and the expenditure of considerable time, and practically every bunion shield thus removed is thereby rendered incapable of further use. Furthermore, any bunion shield attached to the foot with the aid of adhesive, or otherwise permanently attached thereto, is non-sanitary in a high degree in that it seriously interferes with the proper cleansing of the foot and particularly of the part affected and is liable itself to become infectious from impurities, as it, and the parts covered thereby, cannot be thoroughly cleansed by washing upon the foot. Furthermore, washing bunion shields applied with the aid of an adhesive, whether upon or off the foot, renders them stiff and therefore unfit for further use.

The present invention overcomes all these and many other objections, for it will be seen that the bunion shield constructed in accordance with this invention is easily applied and removed by the user himself so that it can be removed, the foot and affected part thoroughly cleansed, and the shield then reapplied without any trouble and in a very short time. There is nothing in the construction of the present shield which will cause it to be injuriously affected by washing. This fact and the ease with which it can be removed and applied, render it capable of use for a considerable time and perfectly sanitary; it is quickly and readily adjusted to feet of all sizes and shapes no matter where the bunion may be located, and when applied and adjusted it will be securely held in place without any injurious binding of the parts. Every part of the device is soft and pliable so that, when in place, the wearer is practically unaware of the fact except for the relief afforded, as it lies perfectly flat and occupies but very little space so that it can be worn with perfect comfort with any shoe.

When the shield has once been adjusted to the foot and secured in place thereon by tying the free ends 50, 52 of the thread, all as above described, it is not necessary in order to remove the shield from the foot, to unknot or cut the thread, as the shield can be readily removed and replaced by slipping the loop 20 off and onto the great toe, and the shield will be held securely in position whenever it is thus replaced.

While details of construction have been shown which have been well adapted to carry the invention into effect, it is to be understood that the invention is not restricted or circumscribed thereby, the essentials of the invention being defined in the claims by intentionally broad language comprehensive of various forms or embodiments of the invention.

10 Having described my invention, what I claim as new and desire to secure by Letters Patent is:

11 1. A bunion shield or protector including a pad; a band to secure said pad in position upon the foot; means relatively to adjust the band and pad and coacting means to secure the band in adjusted position.

12 2. A bunion shield or protector including a pad; a band forming a loop having one end portion secured to said pad; means relatively to adjust the other end portion of said loop and pad and coacting means to secure them in adjusted position.

13 3. A bunion shield or protector including a pad; a band forming a loop having one end portion secured to said pad; a guide for said band; and means relatively to adjust said pad and the other end portion of said loop and to secure them to each other in adjusted position.

14 4. A bunion shield or protector including a pad; a flexible band forming a loop having one end attached to said pad; means relatively to adjust the free end portion of said loop and pad and coacting means to secure said free end portion of the loop to said pad, said pad, band, adjusting and securing means all being of intrinsically yielding or soft material.

15 5. A bunion shield or protector including a pad of relatively soft material, a flexible band having one end portion secured to said pad and a thread threaded through the other end portion of said band and through the material of said pad adjustably to secure said free end portion of the band to the pad.

6. In a bunion shield or protector, a pad 2; a band 8, forming a loop to extend about a toe and having one end attached to said band; a guide 16 for the band, and a thread 50 adjustably to secure the other end of said loop to said pad.

7. A bunion shield or protector including a pad; a band forming a loop for attaching the pad to the foot, one end of the loop being 55 attached to the pad, and a thread for adjustably attaching the other end of the loop to said pad.

8. In a bunion shield or protector, a pad; a band forming a loop for securing the pad 60 to the foot, one end of said loop being permanently attached to the pad, and the other end of said loop being adjustably attached to the pad by a thread threaded first through said band, then through the material of the pad, then through the band, then through the material of the pad again, and finally through the band.

9. In a bunion shield or protector, a pad; a band forming a loop to secure the pad to 70 the foot; and a thread for adjustably securing the band to said pad.

10. A bunion shield or protector including a pad; a band forming a loop for attaching the pad to the foot, one end of said 75 loop being attached to the pad; and a thread passing through the material of said pad and the free end portion of said loop, the construction and arrangement being such that by drawing upon the free ends of said 80 thread said free end portion of the loop and pad can be relatively adjusted and then held in adjusted position by securing the free ends of said thread.

In testimony whereof, I have signed my 85 name to this specification, in the presence of two subscribing witnesses.

ROBERT EDWARD TURNER.
